FIG. 1 is a perspective view of a steering wheel plate bracket with apertures for a gaming chair assembly in accordance with the present invention;

FIG. 2 is an elevational left-side view of the steering wheel plate bracket with apertures for a gaming chair assembly in FIG. 1;

FIG. 3 is an elevational right-side view of the steering wheel plate bracket with apertures for a gaming chair assembly in FIG. 1;

FIG. 4 is an elevational front view of the steering wheel plate bracket with apertures for a gaming chair assembly in FIG. 1;

FIG. 5 is an elevational rear view of the steering wheel plate bracket with apertures for a gaming chair assembly in FIG. 1;

FIG. 6 is a top plan view of the steering wheel plate bracket with apertures for a gaming chair assembly in FIG. 1; and, FIG. 7 is a bottom plan view of the steering wheel plate bracket with apertures for a gaming chair assembly in FIG. 1.
